UNITED STATES PATENT OFFICE

ETTA L. JENKINS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 17,682, dated September 6, 1887.

Application filed August 8, 1887. Serial No. 246,462. Term of patent 3½ years.

To all whom it may concern:

Be it known that I, ETTA L. JENKINS, of the city, county, and State of New York, have invented and produced a new and original 5 Design for a Pattern of a Girl's Costume; and I do hereby declare that the engraved prints accompanying this specification convey to any one accustomed to using paper patterns a clear understanding of how a garment made up by the pattern will appear.

The design shows a dress and basque. The dress displays a waist that exhibits a standing collar, and a skirt exhibiting a broad cluster 15 of side plaits at the center of the front, a box-plait at each side and gathers back of the plaits, and a drapery that appears to extend backward in flat cross-plaits from under the box-plait at each side and fall in a full point nearly to the edge at each side of the center of the back, the front edges of the points describing a 20 rounding outline. The basque displays short, loose-fitting fronts that are straight across their lower edges and appear to be reversed in lapels at their front edges, where they flare to the tops of the shoulders; a close-fitting back 25 that displays an opening at the center below the waist-line, straight lower edges, and curved side edges; a turn-down collar that appears to form notches with the lapels, and coat-sleeves.

What I claim as my invention, and desire to secure by Letters Patent, is—

The design for a girl's costume, as shown in the engraved print accompanying this specification.
